REVERSIBLE BRAKE BEAM STRUT

Thomas K. Cummins, St. Paul, Minn., assignor
to Northern Malleable Iron Company, St.
Paul, Minn., a corporation of Minnesota

Application November 16, 1938, Serial No. 240,742

6 Claims. (Cl. 188—232)

This invention relates to new and useful improvements in reversible brake beams and more particularly to the construction of the strut which provides the fulcrum for the brake beam lever.

5 Reversible brake beams of the compression type, as now commonly constructed, usually comprise a compression member and a tension member, and a strut which is mounted between said members and is adapted for partial rotation to facilitate reversing the brake lever as is well known to the trade. Certain well known struts now in commercial use, are provided at one end with an integral head having an opening adapted to receive the compression member. The opposite 10 end of the strut usually has a seat for receiving the intermediate portion of the tension member. The loop or head at one end of the strut and the seat at its opposite end are so constructed that the strut may be partially rotated to reverse 15 the position of the brake lever. To thus integrally form the head with the strut obviously requires that the loop or opening through the head for receiving the compression member must be loosely engaged with the compression member 20 to permit the head to be rotated thereon. The head of the strut is usually secured in adjusted position with respect to the compression member by a suitable wedge. The body of the strut has an elongated opening for receiving the brake 25 lever, and suitable apertures are provided in the walls of this elongated opening for receiving the fulcrum or pivot pin for supporting the lever. These bearing apertures sometimes become 30 elongated from wear, after which it may become necessary to replace the entire strut. In a strut having an integral head which encircles the compression member, it is necessary to dismantle 35 the brake beam or, in other words, to separate the compression member from the brake heads 40 and tension member in order that the strut may be removed from the compression member. This is objectionable in that it involves considerable labor and may therefore be quite expensive.

An object of the present invention is to provide 45 a simple and inexpensive strut which has been designed to eliminate the objectionable features now present in some well known brake beams and to provide a strut which requires a minimum of machine work, whereby it may be manufactured 50 at very low cost.

A further and more specific object of the invention is to provide a reversible strut having a 55 detachable head at one end provided with means for suitably securing it to the compression member and which head has a socket therein

for rotatably receiving one end of the body of the strut, whereby the strut may readily and conveniently be partially rotated to reverse the brake lever without disturbing the assembly of the compression and tension members, thereby 5 greatly facilitating this operation.

Other objects of the invention reside in the unique construction of the strut which is provided at one end with a head having a portion embracing the compression member and secured to 10 it by suitable means, such as a wedge; in the novel connection between the head and the body of the strut, whereby the strut body may be relatively rotated with respect to the head to 15 reverse the position of the brake lever; in the means for limiting rotary movement of the strut body in the head, whereby it will be properly positioned when rotated from one position to the other; in the simple means for securing the 20 strut body to the head, whereby the body of the strut may be removed from the brake beam for 25 repairs or replacement, when necessary without removing the head from the compression member, and in the means provided for preventing axial movement of the strut body in said head, when 30 the body of the strut is in operative position.

Other objects of the invention will appear from the following description and accompanying drawings and will be pointed out in the annexed 35 claims.

In the accompanying drawings, there has been disclosed a structure designed to carry out the various objects of the invention, but it is to be understood that the invention is not confined to the exact features shown as various changes 35 may be made within the scope of the claims which follow.

In the drawings—

Figure 1 is a view showing a brake beam assembly with the novel strut embodied therein; 40

Figure 2 is an enlarged view of the strut, partially in section, to more clearly show the connection between the strut body and the head provided at one end thereof, which is secured 45 to the compression member;

Figure 3 is a plan view of Figure 2;

Figure 4 is a bottom view of the end of the strut which is secured to the compression member;

Figure 5 is a cross-sectional view on the line 50 5—5 of Figure 2, showing the means for locking the strut body against relative rotation in the head, the two positions of the strut being shown in full and dotted lines;

Figure 6 is a cross-sectional view on the line 55

6—6 of Figure 2, showing the means for preventing longitudinal movement of the strut body in the head, when the body is in operative position;

Figure 7 is a plan view of the strut being 5 removed from the head;

Figure 8 is a side view of Figure 7;

Figure 9 is a view showing a construction of 10 slightly modified form, wherein the head of the strut is secured to the compression member by bolts or rivets; and

Figure 10 is a plan view of Figure 9.

The novel strut herein disclosed is indicated generally by the numeral 2, and comprises a body 3, which preferably is hollow. The body 3 has diametrically opposed elongated openings 4 in the wall thereof for receiving the usual brake lever 5, shown in Figure 1. Suitable bearing apertures 6 are also provided in the wall of the body 3 for receiving a pivot pin 7, which supports the 20 brake lever 5. The brake lever is of conventional construction, and therefore need not be described in detail.

The strut, as best illustrated in Figure 1, is adapted to be interposed between the usual compression member 8 and tension member 9 of the 25 brake beam assembly, generally indicated by the numeral 11. The usual brake heads 12 are secured to the ends of the compression and tension members 8 and 9, respectively, in any suitable 30 manner well known to the trade.

To secure the strut 2 in position between the compression member 8 and tension member 9, it is shown provided at one end with a suitable 35 opening 13, which preferably is elongated slightly to provide clearance for the tension member 9, when the body 3 of the strut is reversed from one position to another. The opposite end of the strut body has a cylindrical portion 14 adapted to be received in a socket 15 provided in a head, 40 generally indicated by the numeral 16. The head 16, as shown in Figures 2 and 3, has a portion 17 which surrounds or embraces the compression member 8. The upper and lower walls of the portion 17 are provided with suitable apertures 18 45 adapted to receive a suitable wedge member 19 which, when received in the apertures 18 will engage the adjacent edges of the channel-shaped compression member 8 and the walls of the apertures 18 adjacent the socket 15. The vertical wall 50 21 of the head 17 is preferably provided with a projection 22 adapted to engage the vertical wall of the compression member 8, when the wedge 19 is driven into place. The lower end portion 23 of the wedge may be bent, as shown in Figure 2, 55 to prevent the wedge from becoming disengaged from the head, when the strut is secured in position in the brake beam.

The cylindrical portion 14 of the body 3 of the strut has a shoulder 24 at one end adapted to 60 engage the adjacent end of the head 16. The shoulder 24 may, as best shown in Figures 1 and 2, be enlarged by the provision of a bead 25 which extends partially around the body 3 of the strut. Notches 26 and 27 are provided between the ends 65 of the head 25 and the ends of an abutment member or lug, generally indicated by the numeral 28.

The cylindrical portion 14 of the strut body has 70 provided thereon, diametrically opposite from the lug 28, a small projection 29, adapted to pass through a recess 31 in the wall of the socket 15, and into a slot 32 provided in said wall, when the cylindrical portion 14 of the strut is inserted into the socket. The slot 32 is disposed at right angles to the longitudinal centerline of the recess 31, and 75 its length is such that the end walls 33 thereof

form limit stops for the rotary movement of the strut body in the socket 15 of the head 16, as will readily be understood by reference to Figure 6. In other words, the limit stops 33 are positioned to be engaged by the lug 29 on the strut body, when the strut beam is rotated or reversed from one position to the other, whereby a suitable key or wedge 34 may readily be inserted into one of the notches 26 or 27 of the strut body and into a suitable opening 35 provided in the wall 10 of the socket of the head 16, as shown in Figures 2 and 3. The wedge 34, when positioned as shown in Figures 2 and 3, locks the body of the strut against relative rotation, whereby it cannot shift from one position to another, when in use. It 15 will also be noted that the slot 32 and projection 29 cooperate to prevent axial movement of the strut body in the socket 15, when the key 34 is positioned as shown in Figures 2 and 3.

The novel strut herein disclosed has been found 20 very practical in actual use and is extremely simple and inexpensive to manufacture in that it may be formed without requiring any machine work. In other words, all of the openings and 25 recesses and slots may be cored in the operation of molding the strut, which greatly reduces the cost of manufacture.

In operation, and it is desired to reverse the 30 brake lever, it is only necessary to remove the wedge 34, whereupon the body 3 of the strut may readily be reversed or partially rotated to bring the brake lever into proper position. When in the desired position, the wedge is again inserted into the opening 35 to lock the body of the strut against relative rotation in the socket 15. If desired, other means than the wedges 19 and 34 35 may be provided for securing the strut in position, but for practical purposes and for economy in manufacture, the wedges herein disclosed are deemed more desirable.

In Figures 9 and 10, there is shown a strut having 40 a T-shaped head, generally indicated by the numeral 36. The head 36 is shown provided at one end with oppositely disposed flanges or lugs 38 adapted to be seated against the inner face 45 of the compression member 8 and secured thereto by such means as bolts 37. Aside from this change, the head 36 is substantially the same as the head 16, shown in the previous figures.

In the drawings, I have shown the end of the 50 strut body which is engaged with the tension member 9 as being apertured to receive said tension member. If desired, this end may be otherwise shaped as, for example, it may be forked, it being understood, however, that it has a suitable seat for receiving the tension member so that the strut cannot become disengaged from the tension member, when the brake beam assembly 55 is in use.

I claim as my invention:

1. A reversible brake beam strut comprising a 60 hollow body having means at one end for engaging the tension member of the brake beam, a head at the opposite end of said body having a socket for receiving a portion of the strut body, a brake lever pivotally supported on the strut body, means whereby said portion may be relatively rotated in said socket to reverse the brake lever, and a locking element for securing the strut body against rotation, when the strut is in 65 adjusted position, said locking element being movable in a direction lengthwise of the strut body.

2. A reversible brake beam comprising a strut 70 body having means at one end for engaging the tension member of the brake beam, a cylindrical 75

portion at the opposite end of said body having a shoulder at one end, a head secured to the compression member of the brake beam and provided with a socket for rotatably receiving the cylindrical end portion of the strut body, a brake lever pivotally supported in the strut body, stops for limiting rotary movement of the strut body with respect to said head to facilitate positioning the strut, when reversing the brake lever, and means 5 exteriorly of said head for positively locking the strut body against rotation, when in either of its adjusted positions.

3. A reversible brake beam comprising a body having a seat at one end for receiving the tension member of the brake beam, a cylindrical portion at the opposite end of said body having a shoulder at one end, a head having a portion embracing the compression member of the brake beam and provided with a socket for rotatably receiving the cylindrical end portion of the strut body, and whereby the strut body may be reversed, stops for limiting rotary movement of the strut body with respect to said head to facilitate positioning the strut, when reversed from one position 15 to another, means for preventing relative longitudinal movement of the strut body with respect to said head, and means for positively locking the strut body against rotary movement, when in either of its adjusted positions.

4. A reversible brake beam comprising a body having a seat at one end for receiving the tension member of the brake beam, a cylindrical portion at the opposite end of said body having an annular shoulder at one end, a T-shaped head adapted to be seated against the compression member of the brake beam, means for securing said head to the compression member, said head having a socket for rotatably receiving the cylindrical end portion of the strut body and whereby 25 the strut body may be rotated to reverse the

brake lever, and means for limiting rotary movement of the strut body with respect to said head, thereby to facilitate positioning the strut when reversing the brake lever, and means exteriorly of the strut body for locking the strut body in 5 adjusted position with respect to said head.

5. A reversible brake beam comprising a body having means at one end for engaging the tension member of the brake beam, a reduced end portion at the opposite end of said body, a head secured 10 to the compression member of the brake beam and provided with a socket for rotatably receiving the reduced end portion of the strut body, a brake lever pivoted in the strut body, spaced notches in the periphery of the strut body adapted to be selectively aligned with a wedge-receiving opening provided in said head, a wedge receivable in said opening to lock the strut body against rotation and to secure the brake lever in adjusted 15 position, and means for preventing relative longitudinal movement of the strut body when in adjusted position.

6. A reversible brake beam strut comprising two parts, one of said parts having one end secured to the usual compression member of the brake beam assembly and having a socket at its opposite end, the other part having one end received in said socket and having a seat at its opposite end adapted to receive the usual tension member of the brake beam assembly, a brake lever mounted in said second mentioned part, means whereby said second mentioned part may be rotatably adjusted with respect to the other part, thereby to reverse the position of the brake lever, and a locking element carried by one of said parts and engageable with notches in the periphery of the other of said parts, thereby to lock said parts against relative rotation, when the brake lever is in either of its adjusted positions.

THOMAS K. CUMMINS. 40
